UNITED STATES PATENT OFFICE

2,560,941

MULTIJET OIL BURNER

Andrew J. Fisher, Sparrows Point, Md., assignor
to Bethlehem Steel Company, a corporation of
Pennsylvania

Application July 10, 1947, Serial No. 759,953

2 Claims. (Cl. 299—140)

1

My invention relates to new and useful improvements in burners, and particularly to high temperature burners of the type in which a liquid fuel is intimately mixed with steam or other atomizing agent.

In open hearth furnaces for making steel the bath is heated primarily by the burner flame. The greatest part of the heat transfer from the flame to the bath is by radiation, and because of refractory limitations, the flame must be placed close to the bath so that the major part of this heat will radiate directly from the flame to the bath.

The working efficiency of an open hearth furnace is especially dependent on the amount of heat extracted from the flame at the first and second doors nearest the burner, because any heat not transmitted in this part of the furnace will be carried over to the third, fourth and fifth doors and cause the furnace to burn in the ports and uptakes of the outgoing end, or else to suffer a loss in tonnage by a necessary curtailment in the amount of fuel used per hour. The problem, therefore, is to create a flame that will heat both the ingoing and outgoing ends of the furnace close to the burning point at the same time.

All of the reactions between the oil, steam and air cannot be completed at the first two doors. The only way to extract maximum heat from the flame at this point is to utilize the partial burning of the oil for further cracking the mixture of oil and steam. This will give a flame of high luminosity due to the free carbon particles produced in the flame, thus increasing its black-body properties. As the amount of heat transferred by a flame is a function of its temperature and emissivity, or radiating power, any addition in flame luminosity will materially increase the radiation exchange between flame and bath.

Since it is the incandescent carbon particles which produce this luminosity, the higher carbon fuels, such as tar, pitch and fuel oil, have considerably greater potential emissivity than natural gas, coke oven gas, or producer gas. However, the burner nozzles should also be kept clean at all times, and fuels of the first type have been found to clog and dirty most of the usual nozzles with carbon deposits very quickly.

The area and shape of the clean burner nozzle and the pressure of the oil and steam determine the shape and conical angle of the flame, and hence the area of the flame envelope.

When burners become dirty, the nozzle area is usually reduced. Since the flow of steam is controlled by pressure, any such restriction in the

2

burner will decrease the amount of steam. The lessened flame radiation of a dirty burner is therefore due to two factors: (1) the reduction in the amount of steam used per gallon of oil; and (2) the increased premixing of the flame envelope and the air stream which lowers the luminosity of the flame. The resultant effect is a lowering of the flame radiation at the first and second doors, with the consequence of a double loss in production, one when the burner is operating in a dirty condition, and another when the furnace is off for refractory repairs caused by dirty burners.

An additional complication is the fact that an efficient open hearth burner must be able to develop a very high temperature non-luminous flame for the initial melting-down period, as well as a lower temperature and highly emissive luminous flame for the period after melting down.

Steam, air and blast furnace gas are the most common atomizing agents, and the factors of the kind, amount and temperature of the atomizing agent used have a particular bearing on the thermal decomposition of the fuel in respect to time.

Good mechanical mixing of the fuel and atomizing agent is also important, being necessary to produce a uniform flame, and is governed by the relationships between the mixer used and the temperatures of the fuel and the atomizing agent.

One object of my invention, therefore, is to provide a liquid fuel burner assembly which is capable of projecting a strongly luminous or non-luminous flame as desired.

Another object is a burner assembly which will remain clean and unclogged during the combustion of carbon rich fuels.

Another object is a burner assembly which can be readily adjusted or controlled from the exterior of the furnace.

Still other and further objects and purposes of this invention will appear hereinafter in the specification and in the appended claims.

Having given above a general description of the advantages of my invention, I shall now in order to make the same more clear refer to the annexed sheet of drawings forming a part of this specification and in which like characters of reference indicate like parts:

Fig. 1 is a vertical transverse section through the burner and mixer assembly;

Fig. 2 is an enlarged detail view of the burner tip;

Fig. 3 is a section taken on the line 3—3 of Fig. 2;

Fig. 4 is a vertical section of the mixer taken on the line 4—4 of Fig. 5;

Fig. 5 is a horizontal section of the mixer on the line 5—5 of Fig. 4; and

Fig. 6 is a section on the line 6—6 of Fig. 1.

Referring now to Fig. 1 of the drawings, the burner 1 proper is provided with an outer tubular casing 2, of steel or the like, to the forward end of which is welded the circular steel end plate 3, having an upper central orifice 4 through which the flanged embossed nose portion 5 of the forwardly tapering multijet nozzle 6, of fast heat conducting metal, preferably a bronze such as silicon bronze, or copper, is inserted and securely brazed as shown in Fig. 2. Said nose portion 5 is of considerable depth, and has a plurality of horizontal rows of parallel evenly spaced small circular discharge passages 7 (nine such passages being shown), having flaring inner ends 8 communicating with the enlarged inner chamber 9 of the nozzle which is provided with interior threads 10 on the inner end thereof.

The rear end of the tubular casing 2 is provided with a welded external annular flange 11, to which is bolted or otherwise secured the flanged casting 12 (Fig. 6) divided by wall 13 into lower and upper chambers 14 and 15 connecting with the inlet pipe 16, distributor pipe 17 and outlet pipe 18 for continuously circulating water or other cooling fluid within said casing 2. Said casting 12 is also provided with a stuffing box 19 through which projects the pipe 20, having its forward end screw threaded by external threads 21 into the threaded end of the nozzle 6. Within said pipe 20 is a steam and mixture conveyer pipe 22 of somewhat smaller diameter, having its forward end 23 beveled and outwardly flared and welded into the forward end of the pipe 20. Welded spacing members 24 and 25 hold the forward ends of the water distributor pipe 17 and the pipe 20 in horizontal position within the outer casing 2.

Screw-threaded onto the rear end of the pipe 20 is a large T 26, and centrally spaced therein and extending forwardly through the conveyer pipe 22 for a considerable portion of its length is the inner fuel conveyer pipe 27, which also serves to provide an annular channel around its outer surface for the passage through said pipe 22 of the steam or other atomizing agent, either alone or in a mixture with the liquid fuel, as hereinafter described. Connected to said T 26 and pipe 27 is a nipple 28, which connects in turn through three-way valve 29 to fuel supply pipe 30.

Said three-way valve 29 is connected by pipe 31, elbow 32, pipe 33, elbow 34 and pipe 35 to the mixer or atomizer 36. Said atomizer may be of the construction shown in my Patent No. 2,242,424, issued May 20, 1941, or other efficient type, but I prefer to use with the present burner the cyclonic atomizer shown in Figs. 4 and 5 of the drawings annexed hereto, in which the fuel entry pipe 35 projects through the upper circular steel end plate 37, to which it is welded, and which end plate 37 in turn is brazed to the edges of the atomizer 36, which may be of bronze or other like metal. A pipe 38 is provided for admitting steam or the like through the spiral trough 39 tangentially into the mixing chamber 40 of said atomizer 36, the bottom aperture 41 of which is connected by the pipe 42 to the T 26.

In operation, for melting down the open

hearth charge, the three-way valve 29 is turned through 90° to divert the oil upwards into the atomizer 36, where it meets the tangentially entering steam and undergoes a swift whirling rotation and thorough mixing. The resultant mixture then passes downward into the T 26, through the conveyer pipe 22, and through the nine nozzle holes 7 into the furnace. The high velocity of the mixture and the spacing of said nozzle holes 7 makes the flame fast burning, non-luminous, and very high in temperature.

After melting down, the three-way valve 29 is reversed through 90° to divert the oil directly into the inner oil pipe 27, which is inside the steam conveyer pipe 22, as shown in Fig. 1. Only the oil is thus diverted, and steam continues to be supplied to the atomizer 36. It is readily seen that the bottom row of the burner holes 7 will be rich in oil and the top row will be lean in oil, with the middle row of holes somewhere in between.

The high ratio of steam to oil, and the pre-heated furnace air which is driven into the flame, cause quick burning of the top layers of the flame. This action cracks the lower layers of the slow burning rich oil flame into small particles of free carbon which cause the flame to be luminous, with maximum flame radiation. The flame is heavy and has a tendency to lay close to the bath, which maximizes heat transfer to the bath and minimizes damage to the roof.

The size and spacing of the nozzle holes 7, and the length of the inner oil pipe 27 are all variables which may be changed to fit the burner to any size of furnace, so as to produce flame radiations of equal and maximum intensity, as measured by a radiation pyrometer, at the first and second doors of the furnace. Nozzle holes $\frac{3}{16}$ " in diameter, spaced $\frac{1}{2}$ " apart on centers, will be found suitable for an average burner.

For the atomizing agent, superheated steam at 375° F., at pressures from 100 to 150 lbs. per square inch, has been found very satisfactory, although a pressure as low as 60 lbs. per square inch has been used. Moreover, compressed air can be further enriched with oxygen to any proportions if higher intensity flames are desired. It is also possible to use one kind of atomization agent for melting down, and another for after melting down.

This burner runs from campaign to campaign without getting dirty or having to be cleaned. Reasons for this effect are the small holes 7 which do not allow radiation in the reverse direction to penetrate far into the holes, the very effective direct water cooling of the holes, the high velocity of the atomizing steam, and the increased pressure and velocity with which the steam and oil mixtures are discharged through the small holes.

The effect of a reliable constant character flame on production is at once apparent, as well as the psychological effect on furnace operators in having a dependable flame which permits operation of the furnace closer to its burning point.

Although I have shown and described my invention hereinabove in considerable detail, I do not wish to be limited narrowly to the exact and specific structure and arrangement stated, but I may use such substitutes, modifications, or equivalents thereof as are within the scope and spirit of the invention and of the appended claims.

Having thus described my invention, what I

claim as new and useful and desire to protect by Letters Patent is:

1. A liquid fuel burner assembly comprising an outer tubular cooling jacket, concentric outer and inner fuel pipes within said jacket, a nozzle of highly heat conductive material within the cooling jacket and connecting to the forward end of the outer fuel pipe, said nozzle having a plurality of rows of spaced horizontal discharge passages, an external atomizer connected to the outer fuel pipe, means for supplying an atomizing agent to the atomizer, and selective valve and conduit means for supplying liquid fuel either to the atomizer or to the inner fuel pipe in accordance with the desired character of the flame. 10

2. A liquid fuel burner assembly comprising an outer tubular casing forming a water jacket, a nozzle having a plurality of small discharge passages within said water jacket, outer and inner fuel inlet pipes also enclosed within said water jacket but insulated therefrom by an air space, the outer fuel pipe being connected to the nozzle and the inner fuel pipe terminating short of the nozzle, an external atomizer wherein steam is introduced tangentially to the fuel and the mixture passes through the outer fuel pipe and the nozzle to produce a non-luminous flame, and a three-way valve connected in the fuel line 20

5

to the atomizer and the inner fuel pipe and arranged for terminating the flow of fuel to the atomizer and directing the flow of fuel into the inner fuel pipe to produce a luminous flame.
